UNITED STATES PATENT OFFICE.

GUSTAV DANIEL AND MAX RUBIN, OF PHILADELPHIA, PENNSYLVANIA.

SHIRT.

SPECIFICATION forming part of Letters Patent No. 367,135, dated July 26, 1887.

Application filed June 7, 1884. Serial No. 134,163. (No model.)

To all whom it may concern:

Be it known that we, GUSTAV DANIEL and MAX RUBIN, of the city and county of Philadelphia, State of Pennsylvania, have invented 5 certain new and useful Improvements in Shirts, of which the following is a specification.

The invention relates to an improved shirt, which is provided at the front and back with tabs that are to be used in place of suspenders; 10 and the invention consists of a shirt provided with a yoke, a back opening, and with parallel tabs attached to and extending down from the yoke at each side of the back opening to the waist of the shirt, and with parallel front tabs 15 attached to the front part of the body of the shirt, one at each side of the bosom, and extended down to the waist of the shirt, said rear and front tabs being provided with button holes or loops at their lower ends.

20 In the accompanying drawings, Figure 1 represents a front elevation, and Fig. 2 a rear elevation, of our improved shirt.

Similar letters of reference indicate corresponding parts.

25 A, in the drawings, represents the body of a shirt, which is provided with a yoke, D, and an opening at the back of the shirt. At the back of the shirt-body A are arranged tabs B', which are attached to the yoke and 30 back, one at each side of and parallel to the back opening, the lower free ends of the tabs B' being provided with button holes or loops C. To the front of the shirt-body A are also attached, one at each side of the bosom, parallel tabs B, which extend, like the rear tabs, 35 down to the waist of the shirt, the front tabs being forked at their lower ends, the free forked ends being provided with button holes or loops C, as shown in Fig. 1.

The tabs and their free ends, provided with 40 button holes or loops, serve as suspenders, and form a permanent part of the shirt.

The tabs can be attached to ordinary shirts, sporting-shirts, boys' waists, blouses, and jumpers, and permit the direct attaching of 45 the pants, overalls, &c., to the shirt, without the use of separate suspenders.

Having thus described our invention, we claim as new and desire to secure by Letters Patent—

50 1. The combination, with a shirt provided with a yoke and an opening at the back, of two vertical tabs secured to and extending from the yoke down the back parallel with the back opening, one on each side of the latter, to the waist of the shirt, substantially as set forth.

55 2. The combination, with a shirt provided with a yoke, of two parallel tabs secured to and extending from the yoke down the back, 60 one on each side of the latter, to the waist of the shirt, said tabs having button holes or loops, and of parallel front tabs secured to the front part of the body of the shirt at each side of the bosom and extending down to the 65 waist of the shirt, said front tabs having button holes or loops, substantially as set forth.

In testimony that we claim the foregoing as our invention we have signed our names, in presence of two subscribing witnesses.

GUSTAV DANIEL.
MAX RUBIN.
